UNITED STATES PATENT OFFICE.

WILLIAM E. WINE, OF TOLEDO, OHIO.

CAR-DOOR MECHANISM.

Application filed January 4, 1926. Serial No. 79,206.

This invention relates to railway cars, and more particularly to means employed in connection with the doors thereof for effecting their closure.

The principal object of the invention, generally stated, is to provide lever means carried by a car, for instance a hopper car, and engageable with the door for forcing the latter to its seat so that a fastening device may then be utilized for positively securing the door in closed position.

The object of the invention, more specifically stated, is to provide a hook-like lever pivotally mounted upon the car and adapted normally to be arranged out of engagement with the door locking or fastening mechanism so as not to interfere with opening movement of the door, the lever being, however, also adapted to be swung into engagement with the door on a partial closing of the door and then operable to force the door from this initial position to final closed position.

Another object of the invention is the provision of means of this character which being attached to the car body renders unnecessary the employment of a pry bar or other implement for forcing the door from partially closed to fully closed position, the use of my invention being of material advantage in that the proper leverage will be assured so that the door may be forced entirely shut, so as to be engaged in final position.

A still further object of the invention is to provide a closing lever which is mounted upon or carried by the bracket structure within which the door hook and locking cam therefor are pivotally mounted, it being consequently possible for the entire assembly; including the bracket, hook, cam and lever to be made and applied as a complete device.

An additional object is to provide a device or structure of this character which will be not only simple and inexpensive to manufacture and install or apply, but which will also be safe and convenient to use, efficient in its action and always ready for service.

To the attainment of the foregoing and other objects and advantages, the invention preferably consists in the combination and arrangement of parts together with the detailed construction, to be hereinafter more fully described and claimed, and illustrated in the accompanying drawings in which:

Figure 1 is a side elevation of a portion of a car hopper and door therefor, the car hopper being provided with a securing hook and locking cam and equipped with the invention, the door being shown in closed position and the closing lever in inoperative or normal position. 60

Figure 2 is a horizontal section taken on the line 2—2 of Figure 1 and showing a 65 plan view of the closing and securing means.

Figure 3 is a view similar to Figure 1 but illustrating the door in partially closed position and engaged by the closing lever ready to be forced shut, and 70

Figure 4 is an elevation looking at the edge of the structure shown in Figure 3.

Referring more particularly to the drawings the numeral 1 designates, generally, a portion of a car hopper including side sheets 75 2 and an inclined bottom 3. The hopper has an open side 4 normally closed by a swingably mounted door 5 of the ordinary construction and mounted in a well known manner. The side sheets carry angular 80 reinforcing members 6 which are preferably outwardly offset at the open side 4, as indicated at 7, to provide an adequate seat with which the door cooperates, the door entering between the members 6 at the opposite sides of the hopper, as is well understood. The numeral 8 designates an angle bar secured across the bottom of the hopper for reinforcing purposes, and 9 represents a reinforcing bar of angular shape riveted or 85 otherwise suitably secured to the angle bar 8, the member 6 and the side sheets 2.

The door 5 has the usual flanges at its edges and is provided at its outer side with a stiffener 10 and door arm 11 formed as an angle bar with its end portion 12 offset outwardly to clear the flange and projecting considerably beyond the edge of the door. 95

Suitably secured upon the side of the hopper is a bracket or plate 13 between which 100 and the hopper is pivoted, at 14, a door hook 15 having two ledges 16 and 17 adapted to cooperate with the end 12 of the door arm for holding the door respectively in partially or fully closed position. A locking cam 18 105 is pivoted at 19 between the plate or bracket 13 and the hopper sheet for engagement with the hook 15 for maintaining the latter in locking relation to the door, as indicated in Figure 1, the ledge 17 engaging the door 110 arm at this time.

Formed upon or secured to the bracket or

- plate 13 and projecting outwardly therefrom is a trunnion element 20 upon which is pivotally mounted an elongated lever 21 constructed and arranged to be brought into engagement with the door arm for forcing the door from partially to fully closed position. This lever is provided at one end with a handle 22 and has its other end formed with a curved nose 23 of such length as to be capable of engagement against the outer face of the door arm for applying pressure to the door. Projecting laterally from the plate or bracket 13 is a suitable stop 24 upon which the lever 21 may rest when in inoperative position, the position of this stop being such that when the lever engages thereon the curved nose 23 of the lever will be located above the path of movement of the door arm 12 so as not to interfere with the opening action.
- Assuming that the door is in open position with the door arm entirely disengaged from the hook 15, to effect closing, the door is swung, by any suitable means or method into partially closed position, the ledge 16 of the door hook engaging over the upper edge of the door arm extension 12. The lever 21 is then swung from its normal or inoperative position shown in Figure 1 upwardly and toward the door so that the curved nose 23 will come into engagement with the outer side of the door arm as indicated in Figure 3. The operator then pulls or pushes, as the case may be, upon the handle to swing the lever still farther so that the curved nose 23 thereof will bring considerable pressure against the door arm, resulting in forcing the door to its seat, whereupon the hook 15 will drop over the door arm extension with the ledge 17 engaging against the outer side thereof. The lever is then swung back into engagement with the stop 24, this being its normal or inactive position.
- While I have shown and described a preferred embodiment of the invention it should be understood that this disclosure is merely illustrative and many changes may be made in the detailed construction and the arrangement and combination of parts provided such modifications constitute no departure from the invention as defined in the claims hereunto appended.
- Having thus described the invention, I claim:
1. In a railway car having a hinged door, a door arm secured to and projecting beyond the side edge of the door, securing means mounted on the car and coacting with the door arm for maintaining the door in partially or fully closed position, and means mounted on the car and engageable with the door arm for forcing the door to fully closed position.
  2. In a railway car, a hinged door, co-

acting means on the car and the door for holding the door selectively in partially or fully closed position, and means pivotally mounted on the car coacting with the door carried means for forcing the door from partially to fully closed position.

3. In a railway car having a hinged door carrying a door arm projecting beyond the side thereof, a hook pivoted on the car and formed with a plurality of ledges selectively engageable with the door arm for holding the door in partially or fully closed position, and lever means pivotally mounted on the car and engageable with the door arm for forcing the door from partly to fully closed position.

4. In a railway car having a hinged door carrying a door arm projecting beyond the side thereof, a hook pivoted on the car and formed with a plurality of ledges selectively engageable with the door arm for holding the door in partially or fully closed position, lever means pivotally mounted on the car and engageable with the door arm for forcing the door from partly to fully closed position, and stop means engageable by the lever for limiting its movement in one direction.

5. In a railway car having a hinged door carrying a door arm projecting beyond the side thereof, a hook pivoted on the car and formed with a plurality of ledges selectively engageable with the door arm for holding the door in partially or fully closed position, lever means pivotally mounted on the car and engageable with the door arm for forcing the door from partly to fully closed position, and stop means engageable by the lever for limiting its movement in one direction and maintaining it normally with its active end out of the path of movement of the door arm.

6. In a railway car having a hinged door carrying a door arm projecting laterally therebeyond, a bracket structure mounted on the side of the car, a hook pivoted within the bracket structure and having successively usable ledges engageable with the door arm for holding the door in partially or fully closed position, and a lever pivotally mounted upon said bracket and having a nose engageable with the door arm when the latter is engaged by one of said ledges, the lever being operable to force the door to fully closed position with the door arm engaged by the other ledge.

7. In a railway car having a hinged door carrying a door arm projecting laterally therebeyond, a bracket structure mounted on the side of the car, a hook pivoted within the bracket structure and having successively usable ledges engageable with the door arm for holding the door in partially or fully closed position, a lever pivotally mounted upon said bracket and having a nose en-

gageable with the door arm when the latter is engaged by one of said ledges, the lever being operable to force the door to fully closed position with the door arm engaged by the other ledge, and means carried by the bracket normally supporting the lever in non-obstructing relation to the path of movement of the door arm.

8. In a railway hopper car having a hinged door carrying a door arm, a bracket structure mounted on the side of the hopper, a door hook pivoted within the bracket and having successive ledges adapted to be engaged with the door arm for maintaining the door in partially or fully closed position, a trunnion member projecting outwardly from the bracket, and a lever pivoted on the trunnion member having a nose engageable with the door arm for forcing the door from partly to fully closed position.

9. In a railway hopper car having a hinged door carrying a door arm, a bracket structure mounted on the side of the hopper, a door hook pivoted within the bracket and having successive ledges adapted to be engaged with the door arm for maintaining the door in partially or fully closed position, a trunnion member projecting outwardly from the bracket, a lever pivoted on the trunnion member having a nose engageable with the door arm for forcing the door from partly to fully closed position, and a stop projecting outwardly from the bracket member and constituting a support for the lever when the lever is in inoperative position whereby said nose will be maintained above the path of travel of the door arm during opening movement of the door.

In testimony whereof I affix my signature.

WILLIAM E. WINE.
